Des. 239,334
Patented Mar. 23, 1976

239,334

HOLDER FOR GRAPHIC DESIGNER'S TOOLS OR THE LIKE

Martin Lowenstein, 463 West St., Apt. H-597
New York, N.Y. 10014

Filed Sept. 24, 1973, Ser. No. 400,234

Term of patent 3½ years

Int. Cl. D3—02

U.S. Cl. D87—1 R

FIG. 1.

FIG. 2.

FIG. 3.

FIG. 4.

FIG. 5.

FIG. 6.

FIG. 1 is a rear, top and left side perspective view of a holder for graphic designer's tools or the like showing my new design,

FIG. 2 is a top plan view,

FIG. 3 is a bottom plan view,

FIG. 4 is a right side elevational view,

FIG. 5 is a rear elevational view, and

FIG. 6 is a front elevational view.

I claim:

The ornamental design for a holder for graphic designer's tools or the like, as shown.
